FRANK W. HOWARD, OF NEW YORK, N. Y.

WATERPROOF CLOAK.

1,229,270.

Specification of Letters Patent. Patented June 12, 1917.

Application filed September 20, 1913. Serial No. 790,862.

To all whom it may concern:

Be it known that I, FRANK W. HOWARD, a citizen of the United States, residing at New York city, borough of Manhattan, county 5 and State of New York, have invented certain new and useful Improvements in Waterproof Cloaks, of which the following is a clear, full, and exact description.

This invention relates to a waterproof 10 cloak.

A principal object of the invention is to produce a cloak which may be very simply constructed and which embodies special features of construction which enable the cloak 15 to be formed from a very simple pattern.

A further object of the invention is to provide a cloak with features of construction which particularly adapt it for being constructed out of a waterproof material 20 such as waterproof paper.

A further object of the invention has been to construct the cloak upon such a pattern as will enable it to be readily held in a flat or folded condition and opened out when intended to be put on.

A special object of the invention is to produce a waterproof cloak of very inexpensive material which will, however, be sufficiently durable to protect the wearer in reaching 30 cover.

The invention consists in the general combination of parts and simplicity of details hereinafter described, all of which contribute to produce a simple and efficient waterproof cloak.

A preferred embodiment of my invention will be particularly described in the following specification, while the broad scope of my invention will be pointed out in the appended claims.

In the drawings, Figure 1 is a front elevation partly broken away and showing in section, a cloak embodying my invention;

Fig. 2 is a plan partly broken away illustrating the form of the pattern from which the cloak is preferably constructed;

Fig. 3 is a horizontal cross-section taken on the line 3—3 of Fig. 1 and further illustrating the construction of the cloak.

While it should be understood that the garment is not necessarily made of two pieces, I prefer to construct it in the manner illustrated in Fig. 2, that is the pattern preferably comprises an upper expande 1 and a lower expande 2. The expande or portion 1 of the pattern is adapted to form the cape of

the cloak and is provided with a central opening or gap 3 from the open point of which edges 4 diverge toward the outer edge. This portion of the pattern is preferably 60 formed with curved edges 5 and at a suitable point I prefer to provide plait lines 6 which radiate from an intermediate point 7, which point is adapted to form the point 8 of the shoulder 9 in the finished cape 10. In 65 order to reinforce the shoulders and relieve the strain of the weight of the material, I prefer to provide shoulder reinforcing strips 11 which may extend radially from the neck opening 3 to the edges. The lower portion 70 or expande 2 of the pattern is preferably of substantially rectangular form and is preferably attached at its upper edge by paste or other adhesive to the lower edge of the expande 1. The adhesive however, preferably does not extend laterally beyond the lines 11^a, and beyond these points 11^a on each side the material is intended to be plaited as indicated by the lines 12. So the skirt portion is attached here to the cape portion only 75 at substantially the middle of the rear side of the skirt portion. I prefer to provide reinforcing strips 13 which extend transversely to the shoulder strips 11 and pass on each side of the neck opening 3 of the pattern. The lower ends of these reinforcing 80 strips 13 are preferably attached between the overlapping adhesive attached edges of the two sections 1 and 2 of the pattern. These strips 13 are preferably attached to the 85 material throughout their entire length and are formed with loose ends 14 by means of which they may be tied together. The body piece or skirt piece 2 of the pattern is also preferably provided with reinforcing strips 90 15 which may be arranged parallel with each other as shown and attached to the material throughout their entire length, leaving loose ends to be tied together as indicated at 16.

In forming the cloak from a pattern such as illustrated, the material is creased at the lines 6 and the pattern section 1 is brought around so as to form a cape in the manner indicated in Fig. 1. The outer portions of 105 the lateral extensions of the skirt section 2 are brought inwardly and forwardly and the upper edges as indicated by the line 17 of this part are secured to the inner side of the forward portion or forward apron 18 110 of the cape. The middle portion of the pattern section 2 between the plaiting lines 12

is attached to the rear apron 18 and forms the back of the cloak, and the edges 4 are made to substantially align with the free vertical edges of the skirt at the front so that the finished garment presents a front dividing line 19 passing down from the neck to the lower end of the garment. In this way the garment is formed into a sleeveless cloak and presents a skirt 20 which is suspended below the cape 10. This skirt is of considerably less width than the cape, and as the upper side edges of the skirt are free, that is, unattached to the cape, the space over them forms armholes 21 for the cloak. 15 The plait lines 12 in the finished garment form plaits 22 which give the skirt a substantially rectangular or box-form and permit the forward or rear sides to separate and thereby enable the skirt to envelop a body; and to expand or contract with the motions of the body. The plait lines 6 conduct to form the plaits 23 of the cape 10 over the arm-holes 21. These plaits 23 in this way form rudimentary sleeves which cling closely to the arm but permit considerable freedom of movement of the arm. The loose ends 14 of the strips or tapes 13 may be tied together as indicated at 24 after the garment has been put on to attach the free edges together at 19. If desired, the edge of the neck opening 3 may be reinforced by an edge band or tape 25.

The material out of which I prefer to form this cloak is very inexpensive waterproof paper such as oil or waxed paper. If this paper is frangible, it may be reinforced by means of the reinforcing strips of cloth or other material which may be arranged if desired, as set forth above.

40 It will be evident that the side plaits 22 adapt the skirt to fold flatly into a small space, and also enable the skirt to open out readily to receive the body.

It is understood that the embodiment of my invention described above is only one of many embodiments or forms the invention may take, and I do not wish to be limited in the practice of my invention nor in my claims to the particular embodiment set forth above.

What I claim is:—

1. A waterproof cloak consisting of a cape having a neck opening, having a forward apron and a rear apron connected to said forward apron, and a skirt connected at the middle portion only of its rear side to the rear apron, and connected at its forward side to the forward apron, said skirt being of considerably less width than said aprons, said cloak having arm openings between the ends of said aprons and the upper edges of said skirt, said cape and said skirt being divided longitudinally throughout their length at the front of said cloak.

2. A waterproof cloak consisting of a cape having a neck opening, having a forward apron and a rear apron connected to said forward apron, and a skirt attached at its rear side to the rear apron, and attached at its forward side to the forward apron, said skirt being of considerably less width than said aprons so as to form arm openings under the ends of said aprons and over the sides of said skirt, said cape and said skirt being divided longitudinally throughout their length at the front of said cloak, said cape having shoulders adjacent said neck opening, and reinforcing strips extending from the said shoulders downwardly and attached below the shoulders to said cloak.

3. A waterproof cloak consisting of a cape having a neck opening, having a forward apron and a rear apron and having a plaited portion connecting the said aprons at the sides, and a skirt attached at its rear side to the rear apron, and attached at its forward side to the forward apron, said skirt being of considerably less width than said aprons so as to form arm openings between the ends of said aprons and over the sides of said skirt, said cape and said skirt being divided longitudinally throughout their length at the front of said cloak.

4. A waterproof cloak adapted to be formed of waterproof paper, consisting of a cape having a neck opening, having a forward apron and a rear apron, said cape having plaited portions at the sides thereof adjacent the shoulders and connecting said aprons, and a skirt extending downwardly from said cape, said cloak having arm-holes below said plaited portions, said skirt having sides with downwardly extending plaits adapting said skirt to fold, and adapting the same to open out when a body is enveloped by said skirt.

5. A waterproof cloak formed of a frangible waterproof material having shoulders and a neck opening therebetween, and having substantially vertical free edges at the front, reinforcing strips attached on said shoulders, extending downwardly in an inclined direction at the front and attached to said cloak at the said free edges, said strips having free extensions projecting beyond said free edges to enable the ends of the strips to be tied together to attach the said free edges together.

6. A waterproof cloak formed of a frangible waterproof material having a cape piece with shoulders and a neck opening therebetween, a skirt piece attached to said cape piece, reinforcing strips attached on said shoulders, extending downwardly and attached to said skirt piece below said shoulders to support the weight of said skirt piece upon said strips.

7. A blank for forming a waterproof cloak having an upper piece to form a cape

- having a substantially circular central gap and diverging edges extending from said gap and having side edges extending up to meet said diverging edges, and a substantially rectangular lower piece extending laterally in both directions from the lower part of said upper piece, and adapted to form the skirt of the cloak, said pieces being attached together with the upper edge of said lower piece overlapping the lower edge of said upper piece.
8. A waterproof cloak consisting of a cape having a neck opening and having a forward apron and a rear apron, and a skirt 15 formed of a separate piece with its rear edge extending up on the under side of the rear apron of said cape and attached thereto, said cloak having arm holes formed between the cape and the upper side edges of 20 said skirt, said skirt and said cape being divided from said neck opening to the lower edge of said skirt, the sides of said skirt under said arm openings having plaits extending downwardly toward the lower edge of 25 said skirt.
9. A blank for forming a waterproof cloak having a cape piece with a substantially circular neck opening and side edges extending substantially circumferentially 30 about the center of said neck opening, and a skirt piece connecting with said cape piece near the lower edge thereof, said skirt piece being of substantially rectangular form and having extensions projecting in both direc-
- tions beyond the side edges of said cape 35 piece.
10. A waterproof cloak having a cape with shoulders and a neck opening between said shoulders, and having a forward apron and a rear apron, a skirt having its rear 40 portion attached to said rear apron, and having its forward portion lying under said forward apron, the upper side edges of said skirt being free with respect to said cape and lying below said shoulders to form arm 45 spaces between the cape and the upper side edges of the skirt.
11. A waterproof cloak having a cape with a neck opening and a forward apron and a rear apron, a skirt having its rear 50 middle portion only attached to said rear apron and having its forward portion attached to said forward apron, the side edges of said skirt being free with respect to said cape to form arm spaces between the upper 55 side edges of said skirt and said cape, said cape projecting out over said side edges, the sides of said skirt having plaits extending longitudinally thereof and in a substantially vertical direction when the skirt is worn to 60 permit expansion and contraction of the skirt.

Signed at New York city, New York, this 19th day of September, 1913.

FRANK W. HOWARD.
